US0D1109167S

(12) **United States Design Patent** (10) Patent No.: **US D1,109,167 S**
(45) Date of Patent: ** Jan. 13, 2026

(54) **DISPLAY SCREEN WITH A GRAPHICAL USER INTERFACE**

(71) Applicant: **Aristocrat Technologies, Inc.**, Las Vegas, NV (US)

(72) Inventors: **Bruno Malta de La Plata**, Espoo (FI); **Eren Özel**, Espoo (FI)

(73) Assignee: **Aristocrat Technologies, Inc.**, Las Vegas, NV (US)

(**) Term: **15 Years**

(21) Appl. No.: **29/915,501**

(22) Filed: **Oct. 31, 2023**

(51) LOC (15) Cl. **14-04**

(52) U.S. Cl.

USPC **D14/492**

(57) **CLAIM**

The ornamental design for a display screen with a graphical user interface, as shown and described.

DESCRIPTION

The sole FIGURE is a front view of a display screen with a graphical user interface showing the claimed design.

The outermost broken line illustrates the display screen and forms no part of the claimed design. The remaining broken lines illustrate portions of the graphical user interface and form no part of the claimed design.

1 Claim, 1 Drawing Sheet
